UNITED STATES PATENT OFFICE.

JACOB STIRISS, OF BROOKLYN, NEW YORK.

COIN-CONTROLLED VENDING-MACHINE.

1,273,013.

Specification of Letters Patent. Patented July 16, 1918.

Application filed August 30, 1917. Serial No. 188,885.

To all whom it may concern:

Be it known that I, JACOB STIRISS, a citizen of the United States, and resident of Brooklyn, in the county of Kings and State of New York, have invented certain new and useful Improvements in Coin-Controlled Vending-Machines, of which the following is a specification.

This invention relates to coin controlled vending machines and especially to machines adapted to automatically dispense and sell small articles such as cakes of candy, chewing gum, boxes of matches and like commodities and its object is to overcome serious objections in machines of this character where the articles may be released by imitation and defective coins or wires and tools while its parts may be simple and substantial, as will be more fully described in the following specification, set forth in appended claims and illustrated in the accompanying drawings, wherein:

Figure 1 is a front view of the complete device.

Fig. 2 shows the interior with the front removed.

Fig. 3 is a side view with the cover broken away.

Fig. 4 is a view of the opposite side.

Fig. 5 is a vertical sectional view with the parts in their normal position and a coin dropped therein.

Fig. 6 is a similar view after the parts have performed their initial movement.

Fig. 7 is a side view with the parts in their final position.

Fig. 8 is a sectional view through the containing chute with the parts at rest.

Fig. 9 is a similar sectional view with the parts delivering an article released.

Fig. 10 shows the parts in their delivering position at the other side of the chute.

Fig. 11 is a detail of the coin stop.

Fig. 12 is a detail of the coin rest.

The device is especially adapted for use in theaters and public halls and is to be located on the back of a chair or on the wall, so that the casing, or cover 16 and the working parts while preferably perpendicular may be inclined at an angle from the perpendicular when the assistance of the coin

may be relied upon to cause the various parts to perform their functions.

The casing 16 has grooves at its sides to receive the edges of a back plate 17 to which is secured, by a tongue 18 and spring fingers 18', the chute 19 in which is deposited the articles to be vended and on which is placed a weighted follower 20 having a lip 21 adapted to engage the lower end 55 of a lever 23 having a barrier 24 to obstruct the coin chute and prevent the operation of the device when the supply of the commodity is exhausted. The said supply is supported and fed outward separately by a tilting shelf 25 whose operation will be more fully explained hereinafter.

In the upper side of the cover 16 is a slot 26 for the insertion of the coin, but the latter cannot enter the chute 27 until the barrier 28 is pushed aside by the coin. This barrier is only operated by a coin of the proper size and by means of a stud 29, also retains the chute 27 and plunger 30 in their depressed position until the release of the said barrier is effected, as shown in Figs. 5 and 6.

This is to avoid injury to or the tearing of clothes in crowded places which result from the plunger projecting at all times.

When the coin C is dropped into the slot 26 it passes down the chute 27 and lodges on the rear end of the coin rest 31 fitted to slide in the slot 32 of a movable box 33 and resting on the end 34 of the tilting shelf 25. This shelf swings on a bar 35 carried by the sides of the delivery box 36 and the said shelf is returned to its proper position by the springs 37 at the left hand side of the apparatus, and whose upper end is connected with one end of the lever 38 pivoted on the plate 17 and whose other end is lodged in a socket in the chute 27 and also tends to raise it to its normal position. The spring 37 is free and performs the double function of returning the parts to their normal positions after the plunger 30 is released.

After the coin has reached the lower end of the chute 27 the inclined rear end 52 of the rest 31 combined with the heart shaped recess 53 at the back causes the coin to

drop to the position shown in Fig. 6. The plunger 30 may now be depressed and is locked down by the engagement of the upper end 27' of the chute 27 with the stud 29. 5 At the same time the finger 39 pivoted to the lower end of the plunger is caused by a cam slot 40, Fig. 7, to swing inward and engage the coin at its center. The rear end of the coin finds lodgment in the recess 32' 10 in the rear wall.

The coin has been resting on the nose 41 of a lever 42 and on being forced down beneath the nose will remain there and block any further operation of the device until 15 the plunger is further depressed and the coin carries the box 33 down until the end 34 of the shelf 25 is rocked and one of the articles dropped into the delivery hopper 43, Fig. 9.

20 The end 34 retards the box 33 from further movement but the chute 27 continues to descend until its cam faced ends 44' engage the sides 45 of the coin rest and force it outward. The box is inclosed by side guides 25' in which the lever 42 is pivoted and its upper ends have the cam faces 44 which play against the sides 45 of the rest 31 and force it out from under the coin when the box reaches its lowest point. The coin rest 31, 30 Fig. 12, has an opening 46 wide enough to permit the passage of the coin but its ledges 47 prevent such passage until the rest has been forced outward. The coin during this 35 operation is held in a transverse position by the fingers 48 punched inward from the sides of the box 33 and when the ledges 47 are removed the pressure of the finger 39 forces the coin through the opening 46 and it drops into the coin box 49. The coin is prevented 40 from being flipped into the chute 50 by a guard 51.

In case a small washer or disk is dropped into the chute 27 it will be of less diameter than the opening 46 and drop through. A 45 washer will not operate the mechanism because the finger 39 will pass through its perforation without resistance while worn coins and thin disks will pass down the chute 50 and into the delivery box 36. Since the 50 opening between 52 and 17 is just wide enough to permit only perfect coins to stop and drop to the transverse position, the worn coin or disk will either fall or wedge in the opening and the plunger will then 55 cause the cam 44' to move the coin rest outward and permit any obstruction to fall through. As above referred to, when the chute 19 is empty the barrier 24 is thrown across the throat of the chute 27, as shown 60 in dotted lines in Fig. 6 and the coin held there or deflected into the box 36.

After the vended article has been dropped by the shelf 25 it falls upon a guide plate 52 at the rear of the box 36 and is there re-

tained by a keeper 53 pivoted across the box 65 as shown in Fig. 9 and adapted to feed out one article at a time. But when the parts are restored to their normal positions as shown in Fig. 8 the keeper blocks the outlet so that no tool or wire can be inserted to 70 remove one of the articles to be vended. Any one of the articles which has been fed outward by the above described operation falls to the mouth of the box 36 to be removed by the purchaser. The keeper has a 75 spring 54 at its front side to prevent its rapid forward movement.

In Fig. 10 will be seen the connection between the shelf 25 and the keeper 53 to cause them to move in unison and which consists 80 of a plate 55 adapted to be depressed by the stud 56 of the shelf 25 which plays in a slot 57 to depress the plate and whose cam slot 58 has playing in it the pin 59 projecting from the side of the keeper 53 adjacent its 85 trunnion 60. Guides 61 and 62 retain the plate 55 against the side of the box and means may be provided to lock the cover 16 to the frame 63 of the outlet to the box 36. At the front end of the shelf 25 are fingers 90 25' which ride under the next to the last article in the chute when the shelf is tipped and support the remaining articles as the last one slides from the shelf as shown in Fig. 9. It will be observed that these 95 fingers move on an arc of which the rod 35 is the center and its movement is therefore nearly horizontal.

The chute 27 has guides 64 and is secured to the plate 17 by means of a button 65 while 100 its lower end is rounded to the diameter of the coin, as at 66 to allow the coin which has passed down it to drop forward as above described, because it is evident that a square or an oblong disk must pass through the 105 chute without operating the mechanism. The lever 42 has a spring 67 at its pivotal point which causes it to exert a continual pressure against the coin rest 31 by means of the side fingers 68 that lie in recess 69 at 110 the outer end of the rest, and lock the box 33 against downward movement by engaging projections 66' on the box, as will be seen in Fig. 5 but release the box when the coin forces back the lever 42 as shown in Fig. 6. 115

The chute 19 may be easily filled with new articles when the cover is removed and it is obvious that the parts may be otherwise arranged or modified without departing from the essential features above described and 120 from the scope of the appended claims.

What I claim is:

1. In a coin controlled vending machine, the combination with a spring, of a delivery shelf, normally retained in its inoperative 125 position by one end of the spring, a coin chute and plunger held by the other end of the spring in receptive and inoperative posi-

tions, and means operated by the plunger when the coin is interposed to tilt the delivery shelf.

2. In a coin controlled vending device, the combination with a spring under tension, of a shelf supporting a column of articles to be vended and retained in its supporting position by one end of said spring, sliding means adapted to support a coin and tilt the shelf, 10 a plunger normally retained in an elevated and inoperative position by the other end of the spring; and a finger on the plunger adapted when depressed to engage the coin.

3. In a coin controlled vending device, the combination with a shifting rest adapted to receive the coin, of a moving box, a supporting shelf for the articles vended and adapted to be tilted by the box to deliver one of the articles, a plunger with a finger adapted to 20 engage the coin and move the box, means for releasing the coin, and a spring under tension and connecting the plunger and shelf to return them to their normal positions.

4. In a coin controlled vending device, the combination with a box adapted to slide vertically, of a coin rest sliding horizontally in the same, a plunger, a coin chute on the plunger and adapted to deliver the coin to the rest, a finger at the lower end of the 30 plunger to engage the coin, a shelf supporting the articles to be vended and adapted to deliver one at a time, means connecting the box with the shelf to tip the latter when the box moves down, means for withdrawing the 35 rest to release the coin, and a spring connecting the shelf and the plunger to return them to their normal position.

5. In a coin controlled vending device, the combination with a box adapted to move 40 downward, of a coin rest adapted to slide across the box and having an opening, a plunger above the coin rest, a chute adapted to deliver the coin to the rest, a finger at the lower end of the plunger adapted to engage 45 the coin, and push it with the box downward, cams adapted to slide the rest so that the coin will fall through the opening, a shelf for the articles to be vended and adapted to be tilted by the box to deliver one of 50 the articles, and a spring connected with the shelf to return it and the box to their normal positions when the coin is released and the plunger to its original place.

6. In a coin controlled vending device, the combination with a chute carrying articles 55 to be vended, of a tilting shelf adapted to carry the articles and deliver one of them at each operation, a keeper adapted to release the article, a box impinging one side 60 of the shelf and adapted to tilt it, a coin rest sliding in the box, a chute adapted to deliver a coin to the rest, a plunger with a finger to engage the coin and push the box and the rest downward to tilt the shelf, cams dis-

placing the rest when the box reaches its 65 downward limit and releasing the coin, a lever locking the coin during the downward movement, and a spring connecting the plunger and the shelf to return them to their normal positions.

7. In a coin controlled vending device, the combination with a box adapted to move up and down, of a coin rest sliding across the box, a lever locking the box and restoring the rest to its normal position, stationary 75 cams shifting the rest, a plunger with a finger to engage the coin and push the box and rest downward, a tilting shelf supporting the articles to be vended, and operated by the box, a keeper operating in conjunction 80 with the shelf, and a spring connecting the shelf and the plunger to return them and their connecting parts to a normal position.

8. In a coin controlled vending device, the combination with a chute for carrying the 85 articles to be vended, of a tilting shelf at the lower end of the same, fingers on the shelf adapted to separate the articles, a keeper normally closing the outlet of the chute, means connecting the shelf and keeper 90 to cause them to operate together, a downwardly moving box adapted to tilt the shelf, a coin rest in the box, a plunger and finger to engage the coin on the rest, and a spring under tension connected at one end to the 95 plunger to retract it and connected to the shelf at the other end to restore it to its normal position.

9. In a coin controlled vending device, the combination with a casing with an outlet at 100 its front and a slot in its top, of a coin chute beneath the slot, a transverse coin rest with an opening at the lower end of the chute, a barrier adapted to be thrown across the end of the chute, a chute for the articles to be 105 sold, a follower adapted to operate the barrier when the supply of articles is exhausted, a downwardly moving box carrying the coin rest, a shelf supporting the articles and having an end adapted to be depressed by the 110 box, a plunger operating above the coin rest, and a spring to return the plunger and the shelf.

10. In a coin controlled vending device, the combination with a casing having an 115 outlet and a slot, of a chute terminating at the outlet, a shelf closing the chute and supporting the articles to be vended, a keeper operating with the shelf and normally closing the outlet, a plunger comprising a coin 120 chute and a finger, means for locking the plunger in an inoperative position, a spring attached at one end to the shelf, a lever attached to the other end of the spring and adapted to force the plunger upward, a 125 downwardly moving box, a transverse coin rest in the box, a lever adapted to lock the coin on the rest until the plunger is oper-

ated, an end on the shelf adapted to be tilted by the box as it is moved downward by the plunger, and means for releasing the coin from the rest so that the box and shelf 5 may resume their former positions.

11. In a coin controlled vending machine, the combination with a casing having a slot in the top, of a coin rest transversely disposed beneath the slot, means for turning the 10 coin from a vertical to a horizontal position,

a plunger adapted to operate upon the coin when it is turned, a box carrying the coin rest and adapted to move downward with the plunger and coin, a containing chute, and delivery means at the bottom of the 15 chute and operated by the box.

Signed at New York, in the county of New York and State of New York this 27 day of August, A. D. 1917.

JACOB STIRISS.
